UNITED STATES PATENT OFFICE.

FRANK W. ETHRIDGE, OF TULSA, OKLAHOMA.

DESIGN FOR A COMBINATION LEAD-SHARPENER AND PIN-TRAY.

48,631.

Specification for Design.

Patented Feb. 29, 1916.

Application filed November 15, 1915. Serial No. 61,695. Term of patent 7 years.

To all whom it may concern:

Be it known that I, FRANK W. ETHRIDGE, a citizen of the United States, residing at Tulsa, in the county of Tulsa and State of Oklahoma, have invented a new, original, and ornamental Design for Combination Lead-Sharpener and Pin-Trays, of which the following is a specification, reference being had to the accompanying drawing, forming a part thereof.

In the drawings: Figure 1 is a perspective view; and Fig. 2 is a plan view of a combination lead sharpener and pin tray, showing my new design.

I claim:

The ornamental design for a combination lead sharpener and pin tray, as shown.

FRANK W. ETHRIDGE.
